Primary Examiner — Susan Bennett Hattan*Assistant Examiner* — Rebecca Tsehay*(74) Attorney, Agent, or Firm* — Grant IP, Inc.(57) **CLAIM**

The ornamental design for a pipette tip sheet assembly, as shown and described.

DESCRIPTION

FIG. 1 is an exploded top perspective view of a horizontally nested pipette tip sheet assembly;

FIG. 2 is a perspective view of the horizontally nested pipette tip sheet assembly shown in FIG. 1;

FIG. 3 is a top view of the assembly shown in FIG. 1 and FIG. 2; and,

FIG. 4 is a bottom view of the assembly shown in FIG. 1 and FIG. 2.
